UNITED STATES PATENT OFFICE.

DOMINICK FASUL, OF NEW YORK, N. Y.

FIRE EXTINGUISHER.

Application filed June 11, 1927. Serial No. 198,099.

The present invention is concerned with the provision of an apparatus primarily adapted for use as a fire extinguisher, and especially designed for the rapid extinction 5 of fires which may occur in oil storage tanks.

The device is in the nature of a unitary steam generator adapted to serve as a temporary cap for a burning oil tank, and to discharge steam into the tank to effectively 10 and almost instantly smother the fire therein.

Under ordinary conditions, when a fire breaks out unexpectedly in a tank, my improved steam generating cap is dropped over the tank and the heat of the fire immediately 15 generates steam which may be directed on to the fire to smother the latter. In every instance where a tank is menaced by fire, the steam generating cap may be heated by some external heat generator so that it will 20 be in readiness for steam discharge as soon as it is placed over the tank.

Obviously, a device of this nature will be rather heavy, and the invention contemplates the provision of means for conveniently handling it, and for shifting it from one tank to another where the tanks are arranged in rows. By this handling means the cap may also be dropped in place over a fire to generate steam before it is emplaced on the tank. 30

In addition to its use as a fire extinguishing apparatus, the device of the present invention may also be used to control the flow from a gushing oil well, the cap being dropped in place over the gusher and acting 35 to conserve and distribute the oil which is rushing therefrom.

Objects of the invention are to provide an apparatus of this character of simple, practical construction which will be rugged, 40 durable and efficient in use, easy to manipulate, and well suited to the requirements of economical manufacture and operation.

With the above noted and other objects in view, the invention consists in certain novel 45 features of construction and combinations and arrangements of parts, as will be more fully hereinafter set forth and pointed out in the claims. The invention may be more fully understood from the following description in connection with the accompanying drawings, wherein—

Fig. 1 is a perspective view showing a device of the present invention in proper position to be dropped over an oil tank.

Fig. 2 is a vertical sectional view therethrough.

Fig. 3 is a sectional plan view on the line 3—3 of Fig. 1.

Fig. 4 is a fragmentary vertical sectional view showing the cap being heated preparatory to its emplacement on a tank.

Fig. 5 is a diagrammatic view showing the fire extinguishing cap mounted to travel on a trolley extending above a line of tanks.

In the drawings I have used the reference numeral 10 to designate an oil storage tank, and the numeral 11 to indicate generally my improved fire extinguishing and steam generating cover. The cover is of approximately conical formation having spaced concentric walls defining a chamber closed at its top and bottom which is adapted to serve as a water chamber, and at its upper end is provided with a hollow neck portion 12 adapted to be closed by a sliding plate 13, 70 this plate being arranged in guides or tracks 14 secured to the top of the cover.

Water may be introduced into the chamber defined by the spaced concentric walls of the cover through an inlet opening at 15, and a visible indication of the water level in 80 the chamber is afforded by a gauge glass 16. The chamber may be drained at any time through a drain cock 17.

Any desired number of radially disposed 85 passageways 18 extend through the double walled cap and receive steam injector nozzles 19, these nozzles being borne in plates 20 which seal the outer ends of the passageways 18. Nozzles 19 are connected to steam 90 lines 21 which tap the water chamber 11, and which steam line is provided with a controlling valve 22.

As best seen in Fig. 1, I have arranged a series of steam pipes near the upper end of 95 the cover which tap the water chamber at points well above the normal water level therein, and have also shown a second series of steam pipes which tap the chamber at a point below the normal water level. These 100 last pipes of course are not to be used until the water level in the unit has been considerably reduced by the formation and discharge of considerable steam.

Means must be provided for bodily 105 manipulating the cap 11 and for simultaneously controlling the valves of the steam nozzle sets.

With this end in view, a trolley 25 is strung between a pair of masts 26 and a carriage 27 is caused to travel along the trolley 110 by hauling lines 28. The cap 11 is provided

with a bail portion 29 suspended from the carriage 27 by a line 30 so that the cap may be raised and lowered relatively to the carriage and dropped in position over a tank 5 10 after the carriage has been shifted the proper distance along the trolley.

The manipulating lines may be conveniently controlled from an operator's platform 31 on the mast 26 and preferably the 10 valve operating chains 32 are also manipulated from this platform.

A chain 32 is associated with each set of steam pipe controlling valves 22, the chain encircling the cap 11, and being connected 15 to all of the valve handles. Intermediate the valves, pulleys 33 are provided to eliminate friction and to prevent slack in the chains.

As above suggested, if a fire unexpectedly 20 breaks out in the tank 10, the cap is quickly manipulated into position and dropped on to the tank. The heat from the blazing oil quickly generates steam in the cap, and by 25 operating the chain 32 of the upper set of valves 22, this steam may be directed through the upper nozzles 19 into the tank, effectively smothering the flames. Due to the fact that the shell-like water chamber 30 is comparatively thin, steam will be generated very quickly. In some instances it may be necessary to subsequently manipulate the lower valves 22, directing a plurality of radial jets of steam from these 35 valves into the tank to complete the operation of extinguishing the fire. The shell is of course water cooled so that it will not burn out under the intense heat of the flames.

In cases where a tank or a series of tanks 40 are threatened with destruction by a near-by fire, the fire smothering cap may be kept in readiness for instant operation by dropping it on to a grate such as 35 in which a fire is burning, thereby getting up steam in the 45 cap which may be used as soon as fire breaks out in any of the tanks. It may be noted that the slide plate 13 is usually closed by a suitable manipulating line 40 as soon as the steam jets are turned on.

50 As suggested above, another possible use for the device is to control the flow of oil from a gusher. To serve this purpose, the steam nozzles 19 are uncoupled and removed, and oil conducting pipes are screwed on to 55 external nipples 41 which encircle the passageways 18. The cap with its flexible pipe lines may then be dropped over a gusher and the sliding top gradually forced to closed position so that all of the gushing oil will 60 be directed to the pipe lines which are connected to the passageways 18.

Obviously, various changes and alterations might be made in the general form and arrangement of the parts described with- 65 out departing from the invention. Hence I

do not wish to limit myself to the details set forth, but shall consider myself at liberty to make such changes and alterations as fairly fall within the spirit and scope of the appended claims.

70 I claim:

1. An apparatus of the class described including a generally frusto conical cap including spaced conical walls, the space between the walls being adapted to serve as 75 a steam and water chamber, said chamber being closed at its top and bottom, steam pipes tapping the chamber and steam nozzles connected to the steam pipes and discharging interiorly of the cap, the pipes 80 tapping the outer wall of the cap, and the cap having passageways therein extending through said walls and space through which the nozzles project.

2. An apparatus of the class described 85 including a generally frusto conical cap including spaced conical walls, the space between the walls being adapted to serve as a steam and water chamber, said chamber being closed at its top and bottom, steam pipes tapping the chamber and steam nozzles connected to the steam pipes and discharging interiorly of the cap, the pipes 90 tapping the outer wall of the cap, and the cap having passageways therein extending 95 through said walls and space through which the nozzles project, said nozzles including flanges closing the outer ends of the passageways to prevent the entrance of air therethrough.

100 3. An apparatus of the class described including a generally frusto conical cap including spaced concentric walls, the space between the walls being adapted to serve as a steam and water chamber, said chamber 105 being closed at its top and bottom, steam pipes tapping the chamber, and steam nozzles connected to the steam pipes and discharging interiorly of the cap, a valve controlling each steam pipe and means for simultaneously operating the valves comprising a flexible device encircling the cap and operatively connecting all of the valve stems.

110 4. An apparatus of the class described including a generally frusto conical cap including spaced concentric walls, the space between the walls being adapted to serve as a steam and water chamber, said chamber 115 being closed at its top and bottom, steam pipes tapping the chamber, and steam nozzles connected to the steam pipes and discharging interiorly of the cap, a valve controlling each steam pipe and means for simultaneously operating the valves comprising a flexible device encircling the cap and operatively connecting all of the valve stems, and a pulley arranged between the valves over which the flexible device runs.

120 5. A fire extinguishing cap for oil tanks 130

or the like including a generally frusto conical shell open at its upper end, and a slide plate for closing said opening, the shell including spaced concentric walls defining a chamber closed at its top and bottom, and serving as a water container, and means for withdrawing steam generated in the shell and directing it inwardly under the shell.

- 5 6. A fire extinguishing cap for oil tanks or the like including a generally frusto conical shell open at its upper end, and a slide plate for closing said opening, the shell including spaced concentric walls defining a chamber closed at its top and bottom, and serving as a water container, and means for withdrawing steam generated in the shell and directing it inwardly under the shell, said means comprising a plurality of sets of exteriorly arranged steam off-take pipes, and 15 20 inwardly discharging steam nozzles disposed in passageways extending through said walls and chamber.

- 25 7. A fire extinguishing cap for oil tanks or the like including a generally frusto conical shell open at its upper end, and a slide plate for closing said opening, the shell including spaced concentric walls defining a chamber closed at its top and bottom, and serving as a water container, means for withdrawing steam generated in the shell and directing it inwardly under the shell, said means comprising a plurality of sets of exteriorly arranged steam off-take pipes, and 30 35 inwardly discharging steam nozzles disposed in passageways extending through said walls and chamber, said sets being arranged at different elevations, and independently operating controlling valve means associated with the different sets.

- 40 8. The combination with a plurality of oil tanks arranged in a line with masts at

opposite ends of the line, and a trolley strung between the masts, a carriage to travel on the trolley, and a frusto conical hollow walled fire-extinguishing cap hung 45 from the carriage, the hollow walls of said cap constituting a steam generating chamber, said cap including a sliding cover, and a plurality of valve controlled steam discharge pipes for conducting steam from the 50 chamber to the interior of the cap.

9. The combination with a plurality of oil tanks arranged in a line with masts at opposite ends of the line, and a trolley strung between the masts, a carriage to 55 travel on the trolley, and a frusto conical hollow walled fire-extinguishing cap hung from the carriage, the hollow walls of said cap constituting a steam generating chamber, said cap including a sliding cover, a 60 plurality of valve controlled steam discharge pipes for conducting steam from the chamber to the interior of the cap, and means controlled from one of the masts for causing the trolley to travel and for raising and 65 lowering the cap.

10. The combination with a plurality of oil tanks arranged in a line with masts at opposite ends of the line, and a trolley strung between the masts, a carriage to 70 travel on the trolley, and a frusto conical hollow walled fire-extinguishing cap hung from the carriage, the hollow walls of said cap constituting a steam generating chamber, said cap including a sliding cover, and 75 a plurality of valve controlled steam discharge pipes for conducting steam from the chamber to the interior of the cap, and means controlled from one of the masts for operating the sliding cover and the valves.

DOMINICK FASUL.
